UNITED STATES PATENT OFFICE.

CLIFFORD W. MARSH, OF BRIDGEPORT, CONNECTICUT.

TYPEWRITING MACHINE.

Application filed July 5, 1922. Serial No. 573,030.

To all whom it may concern:

Be it known that I, CLIFFORD W. MARSH, a citizen of the United States, residing at Bridgeport, county of Fairfield, State of Connecticut, have invented an Improvement in Typewriting Machines, of which the following is a specification.

This invention is directed to typewriting machines and relates to manifolding devices 10 of the general type disclosed in my Patent No. 1,417,472, dated May 28, 1922.

In the ordinary operation of writing and manifolding letters or forms on a typewriter, a great deal of time is lost by having to interleave the sheets with carbon paper and then setting the sheets in the machine preparatory to the writing operation. Time is also lost by having to disassemble these same sheets after the typing 20 is finished.

Also this is true in the ordinary method of filling out forms and simultaneously making manifold copies thereof as, for example, in making out insurance forms by filling in 25 the necessary data in spaces provided in printed blanks, the original of the policy being delivered to the party insured and one or more copies thereof being preserved in the files of the insurance company and the 30 insurance agency. The usual operation involves selecting from the filing case in which the form blanks are stored the required number of copies of the form blank, interleaving and assembling these blanks 35 with the necessary number of carbon sheets and inserting and positioning these interleaved and assembled blanks in the typewriter, all of which must be done before the work of filling in the forms is commenced, thereby consuming in preparation 40 for the work a considerable amount of time in proportion to the time needed for the actual making out of the forms.

The present invention has, therefore, for 45 a primary object the provision of means whereby this loss of time in selecting the sheets, interleaving them with carbon paper, assembling them together and inserting them in the machine may be greatly reduced, 50 and the required number of duplicate copies prepared with a minimum expenditure of time and effort.

Another object of the invention is to provide means whereby a considerable stock of 55 plain writing paper, letter-heads, or blanks for each of a number of different forms,

may be conveniently stored and rendered quickly available for the purpose of preparing the required number of copies of a policy or other document from any of said 60 forms.

It is also an object of the invention to provide means for facilitating the introduction of the required blanks, letter-heads, or plain sheets, into the proper writing position with reference to a typewriter, and for eliminating the necessity of excessive care on the part of the operator ordinarily required in setting up the work-sheets and transfer material to insure the proper 70 manipulation and operation of the mechanism.

It is a further object of the invention to provide a mechanism in which a considerable saving in carbon or transfer material 75 is obtained, and in which there is required no handling of this carbon or transfer paper by the operator so that soiling of the fingers and the resultant soiling of the paper is eliminated.

And it is a still further object of the invention to provide a device of this type in which the operation of making erasures is facilitated.

With the foregoing and other objects in view I have devised the novel mechanism illustrated in the accompanying drawings, in which

Fig. 1 is a perspective view of a standard type of writing machine with my improvements complete.

Fig. 2 is a side elevation thereof.

Fig. 3 is a front elevation of my device as it appears in position on the machine.

Fig. 4 is an end elevation thereof looking from the left of Fig. 3.

Fig. 5 is a transverse sectional elevation substantially on the line 5—5 of Fig. 3.

Fig. 6 is a detailed view of the mechanism for controlling the feed of transfer material. 100

Fig. 7 is a front elevation thereof.

Fig. 8 is a detailed view of the feed mechanism for the transfer material.

Fig. 9 is a front elevation thereof, the driving drum being shown in section. 105

Figs. 10 and 11 are detailed views of elements of this feed mechanism.

Fig. 12 is a detailed sectional view of the means for separating the paper guide-fingers during the operation of severing the work-sheets. 110

Figs. 13, 14, and 15 are detailed views

of the means for guiding the carbon or transfer webs.

Fig. 16 is a side and front elevation of the paper guides, and

Fig. 17 is an end view of the release mechanism for the platen.

The typewriter proper is indicated by the numeral 20, Figs. 1 and 2, and is the standard machine of any desirable type or make which in the present instance is provided with a reciprocating carriage 21, means (not shown) for reciprocating the carriage, and the regular rotatable cylindrical platen 23 Fig. 1 as distinguished from cylindrical platen 33 of my new device. This platen 23 is removably mounted in the carriage 21 by inserting the bearings 24 (Fig. 1) at the opposite ends of the platen in the bearings 25 in the carriage, these bearings in the form 20 shewn being recesses open at the top so that the platen bearings may be inserted therein by merely dropping them into the recesses, and are secured therein to prevent accidental removal by means of the slides 26 which are 25 slidably secured on the carriage by any suitable means such as the screws 27 and may be readily moved to securing or releasing position by the knobs or handles 28. By merely sliding these guides from the position over 30 the recessed bearings, the platen may be readily lifted from the carriage.

The usual paper guide rollers 29, Fig. 5, are provided at the lower side of the platen to securely hold the sheets of paper there- 35 against. I have indicated at 30 in Fig. 5 one of the type bars in the position of making an impression on the paper.

Also carried by the carriage 21 is the usual paper holder and guide 31 at the rear of the platen and the lever 32 for moving the guide rollers 29 from the platen if desired to release the paper or facilitate the insertion of the same. All of this construction, as so far de- 40 scribed, is that of the standard typewriting machine and is not modified in any way to receive and use my improved device.

This device is in reality an attachment which, when used, is mounted on the carriage 21 in place of the regular platen 23. In 45 making the change from using the regular platen 23 to my device all that is necessary is to slide back the guides 26, lift the old platen 23 from the carriage, and then insert my device in place thereof. The platen 33 is sub- 50 stantially the same as the old platen 23 which has been removed and occupies the same position as this old platen did, the platen 33 being provided with bearings 34, Fig. 3, adapt- 55 ed to rest in the bearings 25 of the carriage and being retained in position therein by the slides 26 exactly the same as the ordinary platen 23 is retained therein.

My attachment in the embodiment illus- 60 trated is a complete assembly and includes what I term a carrier which comprises in

combination as a unit, a platen, means for carrying a supply of work-sheets with means for positioning, that is holding, the same upon the platen, means for carrying one or more transfer webs and feeding the same 70 between the work-sheets, and the various guides and operating mechanisms required for the proper use of the attachment. The attachment may be used however, without carrying a supply of worksheets, as individual sheets may be positioned on the platen. 75

The carrier comprises a frame 35; Figs. 4 and 5, which is preferably of sheet metal including spaced end members 36 suitably connected by cross bars 37, Fig. 5, at the rear. These end members are provided with the bearings for carrying the platen, rollers for carrying the work-sheets, and the transfer web supporting and feeding means. 80

The platen 33 is rotatably mounted in bearings at the lower end of the side members and, as mentioned above, is adapted to take the place of the regular platen 23. This platen carries the usual hand knobs 38 at the 85 opposite ends thereof so that the platen may be rotated and is also provided with the ratchet 45 adapted to coact with the pawls of the ordinary spacing mechanism 40, Figs. 1 and 2, to impart the usual step by step ro- 90 tative movements to the platen, this spacing mechanism 40 being the standard spacing mechanism on the typewriter and coacting with a similar ratchet on the ordinary platen 23 to rotate the same. The usual positioning 95 means for the platen is provided. This positioning means may be of any suitable or improved type but I have illustrated a lever 42, Fig. 17, pivoted to the frame at 43 and carrying a roller 44 coacting with the notches 100 in the periphery of a disc 45 to give the proper spacing, the roller being held in these notches by means of a spring 46. This spring will hold the roller either in contact with the notched disc or out of contact with 105 the same to release the platen according to which side of the line joining the pivot 43 and mounting 47 for the spring the roller 44 is moved by the lever 42.

Mounted in the frame of the carrier 110 above the platen are supporting means for the supplies of work-sheets any number of which may be employed as desired. In the present embodiment I have shown three and are preferably rods 48 having bearings in the end members 36 of the frame and adapted to pass through the rolls 49 which comprise the supply of work-sheets. These rods are removably secured in the end members to facilitate the insertion of new rolls of paper or work-sheets, the bearings on one of the end members preferably extending through 115 one edge thereof as shown at 50 in Fig. 3.

Mounted on one of the end members, pref- 120 erably the left hand one shown at Figs. 3, 4,

and 7, are suitable supports for the supply of transfer material which transfer material is preferably in the form of a narrow web 51, Figs. 3 and 4, and is wound in flat rolls 5 of suitable size as indicated at 52. The supports for these rolls comprise studs 53 secured to the frame and carry a core 54 upon which the rolls 52 may be placed there being guiding and holding discs 55 and 56 mounted 10 on these studs between which the rolls 52 are mounted. The core 54 is secured to the inner disc 55 and also secured to this disc on the other side thereof is the toothed ratchet or disc 57. The outer guide disc 56 15 is loose on the stud 53 and is yieldingly held against the end of the core 54 and the roll 52 of transfer material mounted thereon by means of a coil spring 58 secured on the studs by suitable nuts 59, with a suitable 20 washer 60 between the spring and the disc. Mounted on the supporting means for the platen 33 is a toothed disc 61 adapted when the platen is rotated to reciprocate a bar 62, this bar being held at its lower end against 25 the guiding pin 63 and in contact with the disc 61 by means of a spring 64 which is secured to the bar 62 at 65. This bar is pivotally connected at 66 to escapement elements 67, these elements being pivoted to 30 the frame at 68 and connected so as to move simultaneously by means of a link 69 pivoted to the same at 66 and 70. These escapement elements are provided with spaced fingers 71 and 72 which are adapted to cooperate 35 with the teeth of the discs 57 when the ratchet elements are rocked as the bar 62 is reciprocated and allow the discs 57 and the rolls of the transfer webs to which they are attached to rotate to supply the transfer 40 webs as called for by the feeding mechanism in a manner presently to be described. One of the escapement elements 67 is provided with a button 73 which may be pressed by the operator to engage the upper fingers 71 with 45 the ratchet discs and hold the bar 62 out of contact with the ratchet 61 so that the platen may be rotated without affecting the escapement mechanism.

Mounted at the other end of the frame is 50 a drum 74 upon which the used web may be wound. At the opposite end of this drum are the discs 75 and 76 and this drum may be rotated by hand by means of the knob 77. This knob and the outer disc are removably 55 secured to the drum by any suitable means such as a screw threaded engagement therewith. Also connected with this drum, on the opposite side of the end of the frame, is another drum or cup 78 within which is located a convolute spring 79 frictionally engaging the inner walls of this cup as shown at 80, Fig. 8, and secured at its inner end to a shaft 81 rigidly connected with a gear 82. This gear meshes with the idler 83 60 which in turn meshes with the gear 84 se- cured to the platen so that rotation of the platen in the direction indicated by the arrow in Fig. 8 will rotate the gear 82 in the same direction and will tend to wind the spring 79. The friction of the spring against 70 the cup or drum 78 will also tend to rotate the drum 74 to wind the web thereon but, as there is frictional engagement only between the spring and the cup, the gear 82 and, therefore, the platen may if desired be 75 rotated without feeding the transfer web or webs across the front of the platen when the button 73 is depressed and the supply drums 52 are, therefore, held against rotation. The disc 76 is provided on its periphery with teeth 85 adapted to coact with a spring pressed pawl 86 to prevent reverse movement of the drum 74. The gear 84 is loose on the platen shaft 87 and is rotated 80 counterclockwise as viewed in Fig. 8, or clockwise as viewed in Fig. 11, by means of a toothed disc 88 secured to the shaft 87 and adapted to coact with a spring pressed pawl 89 carried by the gear 84. It will thus be 85 seen that rotation of the shaft 87 counterclockwise as viewed in Fig. 8, or clockwise as viewed in Fig. 11 will rotate the gear 84 therewith but the platen shaft may be rotated in the opposite direction without rotating the gear. 90

The transfer webs are guided in the passage from the supply drums or rolls of web 52, Fig. 3, across the front of the platen to the drum 74 by suitable guiding means. At the left hand of the platen, as shown in 100 Fig. 3, and mounted on the end of the frame is a hollow pin or tube 106, Fig. 13, placed at an angle of substantially 45° and when a single carbon copy is made the single transfer web required is passed from either supply drum under the guide pin 108, Fig. 3, and then around the outside of the tube 106, as shown in Fig. 13, and then goes between the guide fingers 109, Fig. 3, horizontally 105 across in front of the platen 33, as shown in Fig. 3, over another guide 110 placed at 45°, under a second guide pin 111 and then to the drum 74. However, when it is desired to make two carbon copies two transfer webs 110 are required and as they are both wound up on the drum 74 the outer web 112 must travel slightly faster than the inner web. If these webs are both passed over the guide tube 106, Fig. 13, in contact with each other, 115 as the outer web moves slightly faster than the inner web and it cannot pass the inner web, it will cause this inner web to slacken in front of the platen. Therefore, to prevent this I provide a separating means preferably an additional guiding means as shown in Figs. 13, 14, and 15 comprising a pin 113 adapted to be inserted in the upper end of the guide tube 106 by means of a knob 114. This pin carries a semi-circular shield 115 spaced from the pin 113 a suitable amount 120

125 130

so that when the pin 113 is inserted in the tube 106 the inner surface of this shield will be spaced from the outer surface of the tube to allow the passage of the inner web 107.

5 The outer web 112 passes around the outside of the shield 115 and so is maintained out of contact with the inner web.

Secured within the frame above the platen is a guide plate 90 having guide fingers 90' secured thereto adjacent its upper edge and extending upwardly in front of roll 49. The plate is provided with vertical slots 91 adjacent its opposite ends in which is adjustably mounted a knife blade 92 by any suitable means such as the nut 93, Fig. 12, threaded on the sleeve 94 which has a flange 95 bearing against the front surface of this plate. By loosening this nut the knife may be adjusted in the slots and then secured in adjusted position. Mounted to rotate in the sleeves 94 are pins 96 provided in their surfaces with a spiral groove 97 and the knife blade 92 is adapted to slide longitudinally of the sleeve 94 on the outside thereof as shown in Fig. 12. The sleeve is provided with a longitudinal slot 98 through which lug 99 carried by the knife blade projects, this lug also extending into the spiral groove 97. Rigidly secured to pin 96 by any suitable means as a screw 100 so as to move with this pin, are guide fingers 101 normally in front of the plate 90 as shown in Fig. 3 to hold the free ends of the sheets of paper in an upright position after they come off the platen. The knife blade 92 is normally spaced a distance forwardly of the plate 90 as shown in Figs. 5 and 12 to allow free passage of the sheets of paper. When it is desired to sever the sheets of paper the operator presses the knife blade inwardly and clamps the sheets of paper between this blade and the plate 90. This operation, through the action of the lugs 99, Fig. 12, in the spiral grooves 97, rotates the pins 96 and swings the guide fingers 101 outwardly toward the ends of the frame leaving the space in front of the sheets of paper free and unobstructed so that these sheets above the knife blade may be torn off along the upper edge thereof. Upon removal of pressure from the knife it is moved outwardly to its normal position by the springs 94' which movement also returns the guide fingers 101 to their normal upright position in front of plate 90.

When the carrier is removed from the machine the free ends of the paper should be secured to prevent their dropping away from the platen to be sure that they are always in proper writing position when the carrier is mounted in writing position on the carriage. Various means may be provided for doing this but I have shown the spring elements 102, Fig. 3, pivoted to the knife blade 92 at 103 and being bent

rearwardly so that, when in the position shown in Fig. 3, they may project through elongated openings 104 in the knife blade and clamp the free ends of paper against the plates 90. These springs may be pulled forwardly and moved to one side of the openings 104 and thus release the paper by means of suitable handles or knobs 105.

The operation is as follows:

When it is desired to use this attachment, 75 the regular platen 23 is removed from the carriage 21 by sliding back the guides 26 and lifting the platen from the carriage. This attachment or carrier including the frame, platen, work-sheets, transfer material, and means for holding and feeding the same, is placed on the carriage in place of the platen that has just been removed, the platen 33 in the attachment occupying the position of the old platen 23 coacting in the same manner with the type bars and adapted to be rotated by the spacing mechanism 40 in the same as was the old platen. As this platen is rotated, it draws from the rolls 49 the paper P the free ends of which 90 have been passed around under the platen and properly located with respect to the transfer webs and then passed between the knife 92 and the guide plate 90. Rotation of the platen step by step in the writing 95 operation will rotate the drum 74 through the gears 82, 83, 84 and the spring 79, Fig. 8, and wind up the used transfer web as fast as this web is released by the escapement mechanism on the supply rolls 52. As 100 this escapement mechanism is operated by the rotation of the platen, if it is desired to advance the work-sheets for any reason by hand, this may be done by means of the knobs 38 in the usual manner. However, 105 as it is undesirable when doing so to advance and thus waste the transfer web, the operator by pressing on the button 73 may hold the supply drums against rotation and the spring 79 will then slide relative to the 110 cup or drum 78. It will be apparent that as this drum is rotated through the instrumentality of the spring after it is wound or placed under tension, the transfer web will always be held under tension from this 115 spring and so will always be held taut across the front of the platen. After the writing has been completed the sheets may be advanced as just described to the proper tearing off position, when the operator 120 presses against the front edge of the knife blade 92 clamping the sheets against the guide plate 90 and moving the guide fingers 101 from in front of the sheets to the opposite edges thereof. The sheets may then 125 be severed by drawing them forwardly over the top edge of the knife blade. The knife blade being then released is moved to its forward position and the guide fingers 101 are turned to holding position as shown in 130

Fig. 3 by the springs 94'. If now it is desired to remove the attachment and use the old platen, the holding springs 102 are placed in holding position, the slides 26 moved to releasing position and the entire attachment removed from the machine by lifting the same from the carriage. In using the old form of platen, holding clips are usually provided at the front thereof such as pivoted plates 117, Figs. 4 and 16, carrying rollers 118 and yieldingly held against the platen. I have provided means for holding these clips forwardly so they will not interfere with the insertion of the platens, such as angle shaped elements 119 secured to the carriage at 120.

It will be apparent from the foregoing description that the carrier including the platen, supply of work-sheets and transfer material may be readily applied to and removed from the machine without the use of tools of any kind, and that as the work-sheets and transfer material are all set up in the attachment and are in continuous rolls, assembling and setting up of the individual sheets is unnecessary and the time required for these operations which is considerable is eliminated. Also as there is no handling of the transfer material by the operator there is no soiling of the fingers or the work-sheets. Further, as the transfer material is in the form of a narrow web and is fed across in the front of the platen in a direction transverse to the direction of feed of the work-sheets, if any erasures are required they may be made by slightly advancing the work-sheets and performing the erasing operation without the necessity of inserting a guard between the transfer paper and the carbon copy. There is material saving in the amount of transfer paper required as all the transfer paper is used uniformly, the feed thereof being proportional to the amount of writing done instead of the amount of work-sheets and paper passed through the machine as in the ordinary method.

In the typewriter employed the regular platen is readily removable from the reciprocating mechanism, and in my device the carrier unit comprising the platen, work-sheets, and carbon paper or transfer material is adapted to be connected with the said reciprocating mechanism of the typewriter, which includes a tension and escapement mechanism, by the same means, so that this carrier is also readily removable to allow the operator to quickly and easily connect this carrier unit with and disconnect it from said reciprocating mechanism, thereby making the carrier unit freely interchangeable with the regular platen provided on the machine. The connection or relation between the carrier unit or the regular platen carried by the machine to the recip-

rocating mechanism is such that the carrier unit or regular platen may be readily disconnected and removed therefrom without breaking down the reciprocating mechanism. In short in applicant's device the carrier unit and the regular platen are freely interchangeable and one may be removed from the typewriter and the other placed in position thereon without breaking down any part of the typewriter, carrier, or regular platen, or changing either one in any way.

Having thus described the nature of my invention, what I claim is:

1. In a manifolding attachment for writing machines having a reciprocating mechanism and means to removably connect a platen with said reciprocating mechanism, a carrier adapted to be removably connected with said reciprocating mechanism and comprising in combination as a unit, a rotatable platen, and means for holding an original and one or more copy worksheets upon said platen when said carrier unit is removed from the machine.

2. In a manifolding attachment for writing machines having a reciprocating mechanism and means to removably connect a platen with said reciprocating mechanism, a carrier adapted to be removably connected with said reciprocating mechanism by said platen connecting means and comprising in combination as a unit, a rotatable platen, and means for holding an original and one or more copy worksheets upon said platen when said carrier unit is disengaged from the reciprocating mechanism.

3. In a manifolding attachment for writing machines having a reciprocating mechanism and means to removably connect a platen with said reciprocating mechanism, a carrier adapted to be removably connected with said reciprocating mechanism and comprising in combination as a unit, a platen, means for holding a plurality of work sheets in superimposed relation upon said platen, and means for holding one or more strips of transfer material transversely of said worksheets.

4. In a manifolding attachment for writing machines having a reciprocating mechanism and means to removably connect a platen with said reciprocating mechanism, a carrier adapted to be removably connected with said reciprocating mechanism by said platen connecting means and comprising in combination as a unit, a platen, means for holding a plurality of work sheets in superimposed relation upon said platen, and means for holding one or more strips of transfer material transversely of said worksheets.

5. In a manifolding attachment for writing machines having a reciprocating mechanism and means to removably connect a platen with said reciprocating mechanism,

- 5 a carrier adapted to be removably connected with said reciprocating mechanism and comprising in combination as a unit, a rotatable platen, and means for holding one or more strips of transfer material in a position transverse to the direction of rotation of said platen.
6. In a manifolding attachment for writing machines having a reciprocating mechanism and means to removably connect a platen with said reciprocating mechanism, a carrier adapted to be removably connected with said reciprocating mechanism by said platen connecting means and comprising in combination as a unit, a rotatable platen, and means for holding one or more strips of transfer material in a position transverse to the direction of rotation of said platen. 70
- 10 7. In a manifolding attachment for writing machines having a reciprocating mechanism and means to removably connect a platen with said reciprocating mechanism, a carrier adapted to be removably connected with said reciprocating mechanism and comprising in combination as a unit, a platen, means for positioning worksheets upon said platen and means for feeding a plurality of transfer webs transversely of the worksheets and separating them to prevent binding. 80
- 15 8. A manifolding attachment for typewriters comprising in combination as a unit a platen, means for holding a plurality of worksheets in writing position on said platen, and means for holding one or more strips of transfer material between the work-sheets and in a position transversely thereof, said unit being adapted to be secured to the reciprocating mechanism of a typewriter by the regular platen securing means. 85
- 20 9. The combination with the printing devices of a typewriter having a reciprocating mechanism and means to removably connect a platen with said reciprocating mechanism, of a carrier removably connected with said reciprocating mechanism and comprising in combination as a unit a rotatable platen and means for carrying one or more transfer webs and feeding the same in a direction transverse to the direction of rotation of said platen. 90
- 25 10. The combination with the printing devices of a typewriter having a reciprocating mechanism and means to removably connect a platen with said reciprocating mechanism, of a carrier removably connected with said reciprocating mechanism and comprising in combination as a unit, a rotatable platen, means for positioning one or more worksheets upon said platen, and means for carrying one or more transfer webs and feeding the same in a direction transverse to the direction of rotation of said platen. 95
- 30 11. The combination with the printing devices of a typewriter having a reciprocating mechanism and means to removably connect a platen with said reciprocating mechanism, of a carrier removably connected with said reciprocating mechanism by said connecting means and comprising in combination as a unit, a platen with said reciprocating mechanism, said carrier removably connected with said reciprocating mechanism by said connecting means, said carrier comprising in combination as a unit, a platen, means for positioning one or more worksheets upon said platen, and means for holding one or more strips of transfer material in writing position and transversely of the worksheets. 100
- 35 12. The combination with the printing devices of a typewriter having a reciprocating mechanism and means to removably connect a platen with said reciprocating mechanism, of a carrier removably connected with said reciprocating mechanism by said connecting means, said carrier comprising in combination as a unit, a platen, worksheets with means for positioning the same upon said platen, and one or more transfer webs with means for feeding the same between said work-sheets in a direction transverse to the direction of the feed of the latter when said work-sheets are on said platen. 105
- 40 13. The combination with the printing devices of a typewriter having a carriage and means for removably mounting a platen on the carriage, of a carrier unit adapted to engage and disengage said carriage and means on said carrier for carrying in combination as a unit, a platen, means for positioning one or more worksheets upon said platen, and means for holding one or more transfer webs between said work-sheets and in a position transversely thereof when the latter are on said platen. 110
- 45 14. The combination with the printing devices of a typewriter having a carriage and means for removably mounting a platen on the carriage, of a carrier unit adapted to engage and disengage said carriage and means on said carrier for carrying in combination as a unit, a platen, means for positioning one or more worksheets upon said platen, and means for feeding one or more transfer webs between said work-sheets in a direction transverse to the direction of the feed of the latter when said work-sheets are on said platen. 115
- 50 15. The combination with the printing devices of a typewriter having a reciprocating mechanism, means to removably connect a rotatable platen with said reciprocating mechanism and means to rotate said platen, of a carrier removably connected with said reciprocating mechanism by said connecting means and comprising in combination as a unit, a rotatable platen occupying the position of the first mentioned platen, means for carrying work-sheets, and means for carrying strips of transfer material transversely of the worksheets. 120
- 55 16. The combination with the printing devices of a typewriter having a reciprocating mechanism, means to removably connect a rotatable platen with said reciprocating mechanism and means to removably connect

- mechanism and means to rotate said platen, of a carrier removably connected with said reciprocating mechanism by said connecting means and comprising in combination as a unit, a rotatable platen occupying the position of the first mentioned platen, means for carrying work-sheets and positioning the same upon said platen, and means for carrying one or more transfer webs and feeding the same between said work-sheets in a direction transverse to the direction of the feed of the latter when said work-sheets are on said platen.
17. The combination with the printing devices of a typewriter having a reciprocating mechanism, means to removably connect a rotatable platen with said reciprocating mechanism and means to rotate said platen, of a carrier removably connected with said reciprocating mechanism by said connecting means and comprising in combination as a unit, a rotatable platen, means for carrying work-sheets and positioning the same upon said platen, and means for carrying one or more transfer webs and feeding the same between said work-sheets in a direction transverse to the direction of the feed of the latter when said work-sheets are on said platen.
18. The combination with the printing devices of a typewriter having a reciprocating mechanism, means to removably connect a rotatable platen with said reciprocating mechanism and means to rotate said platen, of a carrier removably connected with said reciprocating mechanism by said connecting means and comprising in combination as a unit, a rotatable platen, means for carrying work-sheets and positioning the same upon said platen, and means for carrying one or more transfer webs and feeding the same between said work-sheets in a direction transverse to the direction of the feed of the latter when the work-sheets are on said platen.
19. The combination with the printing devices of a typewriter having a reciprocating mechanism, means to removably connect a rotatable platen with said reciprocating mechanism and means to rotate said platen, of a carrier removably connected with said reciprocating mechanism by said connecting means and comprising in combination as a unit, a rotatable platen occupying the position of the first mentioned platen, means for carrying a supply of work-sheets and positioning the same upon said platen, and means for carrying a supply of transfer material and interposing the same between said work-sheets in a direction transversely thereof when the latter are on said platen.
20. The combination with the printing devices of a typewriter having a reciprocating mechanism, means to removably connect a rotatable platen with said reciprocating mechanism and means to rotate said platen, of a carrier removably connected with said reciprocating mechanism by said connecting means and comprising in combination as a unit, a rotatable platen, means connected with said platen and adapted to coact with the rotating means to rotate said platen, means for carrying a supply of work-sheets and positioning the same upon said platen, and means for carrying a supply of transfer material and interposing the same between said work-sheets in a direction transverse to the direction of the feed of the latter when the work-sheets are on said platen.
21. The combination with the printing devices of a typewriter having a reciprocating mechanism, of a rotatable platen connected with said reciprocating mechanism, means for rotating said platen, means for carrying work-sheets and positioning the same upon said platen, means for carrying one or more transfer webs and feeding the same between said work-sheets in a direction transverse to the direction of the feed of the latter when the work-sheets are on said platen, and means connecting the said feeding means with the platen whereby it is operated by rotation of the platen.
22. The combination with the printing devices of a typewriter, of a rotatable platen, means for rotating said platen, means for carrying work-sheets and positioning the same upon said platen, means for carrying one or more transfer webs and feeding the same between the work-sheets in a direction transverse to the direction of feed of the latter when the work-sheets are on said platen, and operating means connecting the platen with said feeding means.
23. The combination with the printing devices of a typewriter, of a rotatable platen, means for rotating said platen, means for carrying work-sheets and positioning the same upon said platen, means for carrying one or more transfer webs and feeding the same between the work-sheets in a direction transverse to the direction of feed of the latter when the work-sheets are on said platen, operating means connecting the platen with said feeding means, and means for at will rendering said feeding means ineffective so that the platen may be rotated without advancing the transfer web or webs.
24. The combination with the printing devices of a typewriter, of a rotatable platen, means for rotating said platen, means for carrying work-sheets and positioning the same upon said platen, means for carrying one or more transfer webs and feeding the same between the work-sheets in a direction

- transverse to the direction of feed of the latter when the work-sheets are on said platen, said means comprising a supply drum, a drum upon which the used web may be wound, a spring, means operated from the platen for storing energy in said spring, and driving means from the spring to the latter drum and having frictional engagement with the spring. 5
- 10 25. The combination with the printing devices of a typewriter, of a rotatable platen, means for rotating said platen, means for carrying work-sheets and positioning the same upon said platen, means for carrying 10 one or more transfer webs and feeding the same between the work-sheets in a direction transverse to the direction of feed of the latter when the work-sheets are on said platen, said means comprising a supply 15 drum, a drum upon which the used web may be wound, yielding means operated from the platen for rotating the latter drum, and means operated by the platen for controlling the rotation of the supply drum. 20
- 25 26. The combination with the printing devices of a typewriter, of a rotatable platen, means for rotating said platen, means for carrying work-sheets and positioning the same upon said platen, means for carrying 25 one or more transfer webs and feeding the same between the work-sheets in a direction transverse to the direction of feed of the latter when the work-sheets are on said platen, said means comprising a supply 30 drum, a drum upon which the used web may be wound, yielding means operated from the platen for rotating the latter drum, escapement means for controlling the rotation of the supply drum, and means for operating 35 the escapement by rotation of the platen. 40
27. The combination with the printing devices of a typewriter, of a rotatable cylindrical platen, means for rotating said platen, means for carrying work-sheets and positioning the same upon said platen, means for carrying one or more transfer webs and feeding the same between the work-sheets in a direction transverse to the direction of feed of the latter when the work-sheets are on 45 said platen, said means comprising a supply drum, a drum upon which the used web may be wound, yielding means operated from the platen for rotating the latter drum, escapement means for controlling the rotation of the supply drum, means connecting the escapement and the platen so arranged that rotation of the platen will operate the escapement, and means for at will rendering said connection ineffective and securing the 50 drum against movement. 55
28. The combination with the printing devices of a typewriter having a reciprocating mechanism and means to removably connect a regular platen with said reciprocating mechanism, of a carrier adapted to be 55 removably connected with said reciprocating mechanism by said connecting means and comprising in combination as a unit a platen, means for carrying work-sheets and means for carrying transfer material, said latter platen adapted to occupy the same position in writing as the said regular platen, means driven from the typewriter for feeding the transfer material between the work-sheets, means for at will rendering said feeding means ineffective, and means for advancing the work-sheets. 70
29. The combination with the printing devices of a typewriter having a reciprocating mechanism and means to removably connect a regular platen with said reciprocating mechanism, of a carrier adapted to be removably connected with said reciprocating mechanism by said connecting means and comprising in combination as a unit a platen, means for carrying work-sheets, and means for carrying a plurality of strips of transfer material, means on said carrier for guiding said strips of transfer material in a direction transverse to the direction of feed of the work-sheets, means to separate said strips of transfer material to prevent binding, and means for keeping the transfer material taut across the face of the platen. 80
30. The combination with the printing devices of a typewriter, of a platen, means for carrying a supply of work-sheets and positioning the same on said platen, a movable knife for severing the work-sheets, 85 guide means for holding the sheets after leaving the platen, and means operated by movement of the knife to move the guide means to a non-holding position during the severing operation. 90
31. The combination with the printing devices of a typewriter, of a platen, means for carrying a supply of work-sheets and positioning the same on said platen, a movable knife for severing the work-sheets, upright supporting elements forwardly of the work-sheets for supporting the same after leaving the platen, and means operated by movement of the knife for moving said elements to the side of the sheet during the 95 severing operation. 105
32. The combination with the printing devices of a typewriter having a reciprocating mechanism and means to removably connect a regular platen with said reciprocating mechanism, of a carrier adapted to be removably connected with said reciprocating mechanism by said connecting means and comprising in combination as a unit a platen, means for carrying work-sheets, and means for carrying transfer material, said latter platen adapted to occupy the same position in writing as the said regular platen, means on said carrier unit for guiding the work-sheets as they pass the platen, 110 115 120 125 130

means for severing the work-sheets as required, and means to move the work-sheet guides to a non-guiding position during the severing of the work-sheets.

6 33. The combination with the printing devices of a typewriter having a carriage and means for removably securing a platen in the carriage, of a carrier adapted to be removably mounted in the said platen securing means and comprising in combination as a unit, a platen, means for carrying a supply of work-sheets with means for positioning the same upon said platen, and retractable means for securing the free ends 10 of the work-sheets when the carrier unit is removed from the carriage.

34. The combination with the printing

devices of a typewriter having a reciprocating mechanism and means to removably connect a regular platen with said reciprocating mechanism, of a carrier adapted to be removably connected with said reciprocating mechanism by said connecting means and comprising in combination as a unit a platen, means for carrying work-sheets, and means for carrying transfer material, said latter platen adapted to occupy the same position in writing as the said regular platen, and means on said carrier unit for securing the free ends of the work-sheet when the 20 25 carrier is removed from said reciprocating mechanism.

In testimony whereof I affix my signature.

CLIFFORD W. MARSH.
